US0D1049740S

(12) **United States Design Patent** (10) **Patent No.:** **US D1,049,740 S**
(45) **Date of Patent:** **** Nov. 5, 2024**

(54) **DISPENSER**

(71) Applicant: **Brio Water Technology, Inc.**, City of Industry, CA (US)

(72) Inventors: **Arman Melkonian**, La Cañada Flintridge, CA (US); **Mark Melkonian**, Northridge, CA (US); **Ryan Nguyen**, Westminster, CA (US)

(73) Assignee: **Brio Water Technology, Inc.**, City of Industry, CA (US)

(**) Term: **15 Years**

(21) Appl. No.: **29/930,770**

(22) Filed: **Mar. 1, 2024**

(51) LOC (14) Cl. **07-01**

(52) U.S. Cl.

USPC **D7/311**

(57) **CLAIM**

The ornamental design for a dispenser as shown and described.

DESCRIPTION

FIG. 1 is a front, top perspective view, showing my new design for a dispenser;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines show portions of the dispenser that form no part of the claimed design.

1 Claim, 7 Drawing Sheets
